UNITED STATES PATENT OFFICE.

ARTHUR O. COREY, OF COUNCIL GROVE, KANSAS.

COMBINED DENTAL MALLET AND PLIERS.

SPECIFICATION forming part of Letters Patent No. 433,592, dated August 5, 1890.

Application filed December 26, 1889. Serial No. 335,083. (No model.)

To all whom it may concern:

Be it known that I, ARTHUR O. COREY, of Council Grove, in the county of Morris and State of Kansas, have invented a new and 5 Improved Combined Mallet and Pliers for Dentists' Use, of which the following is a full, clear, and exact description.

Heretofore it has been customary when filling cavities in teeth to use a separate tool for 10 the insertion of the filling wads or granules within the prepared tooth-cavity. The pliers thus employed were then discarded and a plugging-mallet with either a separate or attached punch substituted, with which the loose 15 pellet of filling was securely compacted by successive blows of the mallet on the punch. There are a number of filling-pellets employed in closing a large cavity, as but small amounts of the filling material can be inserted 20 at one time, if good results are desired. Consequently a considerable amount of time is consumed in the operation. It is evident that to lay down and take up the separate tools used in the insertion and subsequent malletting of a tooth-filling considerably increases 25 the time occupied in inserting material and plugging a carious tooth.

The object of my invention is to provide a combined mallet and pliers for dentists' use, 30 so constructing the same that a neat, compact, practical, and efficient instrument is afforded, whereby the inserting of the filling material and successive malletting of the same may be effected without exchanging tools, the pliers 35 being always in position in the hand of the operator, as is also the mallet, ready for alternate and immediate use.

To effect the object sought, my invention consists in the construction and combination 40 of parts, as hereinafter described, and pointed out in the claims.

Reference is to be had to the accompanying drawings, forming a part of this specification, in which similar letters of reference indicate 45 corresponding parts in all the figures.

Figure 1 is a perspective view of the combined implement in the hand of an operator, the pliers being in use to grip and convey a piece of filling material to a tooth-cavity. 50 Fig. 2 is an enlarged view, in elevation, of the

mallet and pliers; and Fig. 3 is an end view of the mallet-block, showing the pliers combined therewith.

A represents the mallet-block, which may be made of any suitable heavy and hard 55 material, metal being preferred. Different shapes may be given to the mallet-head, the most available for its use being represented in the drawings, as the enlarged middle portion affords weight, while the parallel flat ends 60 *a* are equally serviceable for use on a punch.

The preferred form for the pliers is here represented, although equivalent shapes may be used which fall within the scope of the invention. As shown, the pliers B provide a 65 handle for the mallet-block A, and consist of a single strip of elastic steel, which is given a return bend at *b*, the material being flattened and widened at this point to afford a grip-piece for the hand of the operator. One 70 limb *c* of the pliers is straight, and is inserted through an orifice formed as a slot through the center of the mallet-block, considered side-wise, which slot is of such proportionate dimensions as to receive the limb *c* and fit it 75 closely when it is inserted to a point near its longitudinal center.

The limb *b* of the pliers B is curved laterally at a point *d'*, opposite the mallet-block A, and from the forward terminal of this lateral 80 curvature the free end *d* of the limb *c* is tapered gradually to its terminal. The portion *c'* of the limb *c* which projects beyond the mallet-block is tapered to mate the similar portion *d* of the limb *d*, both these portions 85 being preferably bent at the same point *e*, thereby providing "pick-up" points to the pliers, as shown at *e'*.

In use the pliers are gripped, as shown in Fig. 1, and a small "wad" or pellet of the filling material is raised by the points *e'* and conveyed to a tooth-cavity which is to be filled. When properly deposited therein, the operator inserts the plugging-punch and at once commences the malleting operation, not 95 having to throw down the pliers and find the mallet.

Having thus described my invention, what I claim as new, and desire to secure by Letters Patent, is—

1. The combination, with a mallet-block, of pliers the points of which project in advance of the mallet-block, substantially as set forth.
2. The combination, with a mallet-block that is slotted to receive a pliers' limb, of pliers having one limb connected to the mallet-block and its pick-up ends projected in advance of the mallet-block, substantially as set forth.
3. The combination, with a mallet-block having both of its ends adapted for use as mallet-faces, and its body slotted laterally for the

reception of a pliers' limb, of pliers comprised of two limbs bent from a single strip, one limb being secured in the slot of the mallet-head and the free ends of its limbs projected in advance of the mallet-block and bent to produce pick-up joints, substantially as set forth. 15

ARTHUR O. COREY.
